UNITED STATES PATENT OFFICE.

SCOTT M. BURKETT, OF TARENTUM, PENNSYLVANIA.

CLOTHES-WRINGER ATTACHMENT.

Application filed October 11, 1923. Serial No. 667,916.

To all whom it may concern:

Be it known that I, Scott M. BURKETT, a citizen of the United States, residing at Tarentum, in the county of Allegheny and 5 State of Pennsylvania, have invented certain new and useful Improvements in Clothes-Wringer Attachments, of which the following is a specification.

The present invention relates to an attachment for clothes wringers.

The object of the invention is to furnish means whereby the rolls of clothes wringers are constantly kept clean. For this purpose one or more brushes are attached to the 15 wringer along the rolls and held yieldably against the latter. In this manner whenever the wringer is used and the rolls rotated, the brushes come into action and scrub the rolls clean so that after one article has been 20 passed through the wringer the next article will not be affected by coloring matter from the previous article.

In the accompanying drawing, one embodiment of the invention is illustrated, 25 and—

Figure 1 is a front elevation of a wringer with a brush secured in position;

Figure 2 is an elevation of the brush in larger scale;

30 Figure 3 is a section along line 3—3 of Figure 2, and—

Figure 4 is a section along line 4—4 of Figures 1 and 3.

In the drawing, reference numeral 10 represents a wringer of any known construction 35 provided with a lower roll 11 and an upper roll 12 revolvably mounted in suitable bearings 13, and the upper roll being pressed against the lower one by means of a spring 40 14, the pressure of which may be adjusted by a screw 15. These parts are common to all wringers and form no part of the present invention.

The brush attachment consists of a two 45 part casing 16 composed of a top shell 17 and a bottom shell 18. The casing is of sufficient length to bridge across from one upright to another on the wringer and is adapted to be secured thereon by bolts or 50 screws 19 engaging in apertures 20 formed in ears 21 projecting from each end of the

top shell 17. The said top shell has a back wall 22 and inwardly diverging end walls 23. The top shell has also a roof 24 terminating with a narrow downwardly directed 55 front ledge 25. The bottom shell 18 has a floor plate 26, a back wall 27 and inwardly diverging end walls 28 so that the bottom shell fits snugly in the top shell. The former has an upwardly turned front ledge 29, the 60 top edge of which meets the bottom edge of the ledge 25 on the top shell. The middle portion of the ledge 29 is recessed, as at 33, to form a passage through which the bristles 30 of the brush 31 extend. The 65 top and bottom shell are secured together by means of bolts and nuts 32 which engage in circular apertures provided in the rear and side walls 22 and 23 of the top shell, while corresponding vertical slits 34 are 70 furnished in the rear wall 27 of the bottom shell.

The brush has preferably a wooden back 75 engaging with the inside of the ledges 25 and 29 and is pressed against the same by a flat spring 35 inserted between the brush and the rear wall 27 of the lower shell 18. At 36 is shown a leather backing placed between the spring 35 and the rear wall 27.

As illustrated in Figure 1, a brush of the 80 construction just described is placed along the lower roll 11 of the wringer. There might be one of these brushes on each side of the lower roll and other brushes similarly provided for the upper roll 12. When the 85 brushes are attached to the wringer, the ends of the bristles 30 are pressed against the rolls by their springs 35 so that when the wringer is in operation and the rolls revolve therein, the cylindrical surfaces of the 90 rolls is constantly scrubbed by the brushes and kept clean.

A further function of the brushes is to 95 prevent the washed material from becoming tangled and wound around the rolls.

Having thus described the invention, what is claimed as new is:

An attachment for clothes wringers comprising a hollow casing consisting of an upper shell and a lower shell fitted snugly 100 in the upper shell, said shells being provided with ledges extending toward each other at

their inner sides and the ledge on the lower shell having a recess in its edge, means for securing the shells together, means for securing the ends of the upper shell to the 5 wringer frame, a brush disposed within the casing with its bristles extending through the recess in the ledge on the lower shell

and guided by the same and the ledge on the upper shell, and means within the casing for yieldably holding the brush to a 10 wringer roll.

In testimony whereof I affix my signature.

SCOTT M. BURKETT. [L.S.]
